UNITED STATES PATENT OFFICE

2,462,062

FUSE

Donald R. Beeman, Wharton, N. J., assignor to
the United States of America as represented by
the Secretary of War

Application June 23, 1942, Serial No. 448,162

1 Claim. (Cl. 102—79)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a fuse and in particular to a type carrying a separable portion of a powder train in a centrifugally movable housing.

It is an object of the invention to provide such a fuse which shall have improved safety in the event of premature setting off of the detonator. More specifically it is an object of the invention to provide such a fuse in which the centrifugal member is sealed in its slide passage by the forces of premature explosion of the detonator. It is a further object of the invention to provide improved means of retaining the centrifugal member in armed position after normal functioning.

These and other objects are attained by locating the detonator closely adjacent the slide passage containing the centrifugal member with only a small web of material in the fuse body between the two which web is easily forced into gastight engagement with the centrifugal member to prevent passage of gaseous detonation products to the offset portion of the powder train. The sliding member is retained in armed position by means of a ball which drops into a circular groove either under centrifugal action or creep.

The specific nature of the invention as well as other objects and advantages thereof will clearly appear from a description of a preferred embodiment as shown in the accompanying drawings in which:

Fig. 1 is an elevational view in axial section of a fuse housing, and

Fig. 2 is a sectional view taken on the line 2—2 of Fig. 1.

Referring to the drawing by characters of reference, there is shown a fuse body 1 containing a forwardly located booster 2 retained by a screwed cap 3 with sealing disk 4. A central longitudinal bore 5 passes through the body 1 and serves as a firing communication with the booster. An oblique bore 6 of substantially larger diameter than the bore 5 intersects the central bore 5 and has an eccentric counterbore 7 to accommodate the eccentric head 8 of a sliding bolt 9 in the bore 6. The bore 6 is inclined from its open end toward the rear at an angle approximating (though not necessarily) twenty degrees to a plane normal to the longitudinal axis of the body 1, and this bore extends across

2

the bore 5 and beyond a distance of approximately three times the diameter of the bore 5 to a blind and stopping short of the periphery of the body 1 a substantial distance. A tapped counterbore 10 concentric with eccentric counterbore 7 receives a closure cup nut 11 which serves as a seat for a spring 12 engaging around a central boss 13 on the eccentric head 8 of the bolt 9. An obliquely transverse bore 14 in the bolt 9 contains a portion of the booster charge 2 or other fire communicating medium, this bore being maintained in parallelism with the central bore 5 of the fuse body by the eccentricity of the sliding bolt head 8 and the counterbore 7.

15 A first counterbore 15 in the other end of the central bore 5 receives a washer 16 and a detonator 17. A second counterbore 18 is threaded to receive a detonator-retaining ring 19 and a third counterbore 20 is threaded to receive a head portion 21 of the fuse. A central bore 22 in the inner end of the head portion receives a hammer plunger 23 of substantial mass for movement by inertia. Fitted in a radial slot 24 in the plunger is a centrifugal block hammer 25 rotatably mounted in the plunger on a transverse axis intersecting the axis of the fuse by a pin 26. The hammer 25 has parallel sides normal to the pin 25, and is fitted in the slot so that these sides lie equally spaced from the axis of the fuse. The hammer 25 has a bore 27 rearward of the pin 26 at initial or unarmed position of the hammer receiving pins 28 which are initially engaged in and slidably radially under centrifugal action into bores 29 in the plunger so as to clear the hammer, but are normally held in hammer locking position by means of springs 30 confined in the bores 29. A sleeve 31 around the plunger retains the pins 28 and is secured by a pin 32. The plunger is held in the rearward position in 35 the bore 22 by means of a spring 33 fitted in a bore 34 in the plunger and in a guide tube 35 carried by the body 14, which guide tube is also slidably engaged in the bore 34. The plunger and hammer correspond to prior known devices 40 of similar function, the hammer having a firing pin thereon which projects laterally out of line with the detonator at initial (safe) position of the hammer, but moving into line with the detonator under centrifugal force.

45 50 The bottom of the counterbore 15 is located adjacent the oblique bore 6 and this results in a relatively thin web portion 36 between the detonator 17 and the inner end portion of the bore 6. This web portion is deformable by explosion 55 of the detonator 17 when the products of such

explosion are confined by the bolt 9. A cavity 37 in the oblique bolt 9 forms a prolongation of that portion of the central bore or flash hole 5 which is between the primer and the oblique bolt. A ball 38 is received in a cavity 39 in the forward side of the bolt 9, and a counterbore 40 in the nut 11 is of sufficient diameter to receive the ball 38 freely under centrifugal action and "creep" effects. It should be noted, however, that the radius of the counterbore 40 is such that the ball 38 is prevented from escaping entirely from the cavity 39, so that while the ball engages the wall of the bore 40, any tendency of the bolt 9 to return will be prevented by engagement of the ball between the rear side of the cavity and opposing inner end surface of the counterbore 10.

The construction shown renders the fuse safe in the event of accidental discharge of the detonator because the path which the detonation products must follow to reach the displaced ignition train would be between the bolt 9 and the abutting surface of the bore 6, commencing at the central bore 5. Any premature explosion of the detonator prior to sliding of the bolt 9 into armed position would result in a forcing of the web structure 36 against the bolt 9 resulting in an effective seal of the only path to the offset part of the ignition train carried in the bore 14 through the bolt. The provision of cavity 37 in the slide bolt 9 permits by-passing of the path to the powder train for a very brief interval to ensure that no gases will enter between the bolt and its housing prior to sealing of the web. If these gases were permitted to enter between the bolt and surface of the bore 6, a balancing pressure might be set up which would militate against the effective sealing of the web.

I claim:

A fuse comprising a body portion having a fire communicating passage, a bolt receiving bore across said passage and at an oblique angle thereto, a bolt slideably moveable in said bore between extreme armed and unarmed positions.

a second fire-communicating passage in said bolt alignable with the first fire communicating passage in the armed position but rearwardly slideable down said bore in the unarmed position, a detonator in said body in communication with the first fire communicating passage, a portion of the material of said body extending between said detonator and said bolt immediately adjacent to said bolt, said portion being constructed to yield to the pressures produced by the explosion of the detonator when fired while the bolt is in said safe position, whereby to seal the opening between said bolt and said body portion against passage of gases on premature approach of said detonator when said bolt is in the safe position, a cavity in said bolt at its forward side, a sphere loose in said cavity, and a receiving groove for said sphere in said body portion to lock the bolt against return sliding, said groove being of a depth substantially less than the diameter of the sphere, said cavity being spaced from said groove when the bolt is in said safe position a distance equal to the distance between said safe position and said armed position of the bolt, whereby under the combined action of creep and centrifugal force said sphere is urged toward said groove when said bolt is in the armed position.

DONALD R. BEEMAN.
